UNITED STATES PATENT OFFICE

2,180,447

REFRIGERATING SYSTEM

Lyman F. Whitney, Cambridge, Mass., assignor,
by mesne assignments, to Stator Corporation,
a corporation of Rhode Island

Application October 27, 1937, Serial No. 171,325

21 Claims. (Cl. 62—115)

This invention relates to an improved refrigerating apparatus of the general type disclosed in the United States Patent No. 1,761,551 to Eastman A. Weaver and in my United States Patent

5 No. 1,756,802.

The above-identified patents disclose a system employing water as a refrigerant and mercury as a propellant. While water has very advantageous characteristics for this purpose, it often is desirable to provide a refrigerant which has a lower freezing point. Furthermore, while water and mercury are liquids which are substantially immiscible under all ordinary conditions, I have found that under certain operating conditions 10 very fine particles of mercury, such as are provided by mercury vapor or by mercury fog, when contacting water, tend to assume an extremely finely dispersed condition in the water to form therewith a more or less stable sludge. For example, when some mercury passes with the water vapor to the refrigerant condenser, a sludge may be formed. This sludge drains to the cooler, where it may gradually become heavier as more sludge is received from the condenser. Furthermore, mercury vapor or fog may occasionally pass 15 directly from the aspirator mixing chamber into direct contact with the water in the cooler, thus causing the formation of a sludge. The tendency to form sludge is aggravated in a system having walls of ordinary steel. The proportions of mercury and water in the sludge may vary widely, and the sludge in many respects resembles mud.

I call suspension of mercury in water a sludge suspension. Depending upon operating conditions, this suspension may be either lean or rich in the mercury. If only a thin sludge suspension exists in the system, the effects are negligible. However, the mercury tends to settle in such a body of sludge suspension; the settling mercury 20 may not coalesce, but rather may form a mud-like sludge deposit. Should the factors that cause the original suspension continue to be present, they cause the formation of further sludge suspension from which additional mercury settles, thus augmenting the mud-like deposit. When the sludge suspension is relatively rich in mercury, the tendency to form the mud-like deposit is increased. Any type of sludge except a thin sludge suspension is deleterious because it involves a collection of mercury where it is not needed, thus materially increasing the total amount of the relatively expensive mercury required in the system. A sludge deposit is also deleterious since it tends to impede free circulation of the fluids through pipes.

As taught more particularly in my copending application Serial No. 207,267, filed May 11, 1938, an aqueous refrigerant comprising a solution of a suitable anti-freeze agent in water may conveniently be employed in a system of this character when it is desired to have cooler temperatures substantially below 0° C. Among such anti-freeze agents are methyl Cellosolve, either as commercially obtained or in a chemically pure form, ethylene diamine and morpholine. When 10 a system having conventional steel walls is employed, I prefer to use an anti-freeze agent having its major part consisting of methyl Cellosolve and preferably including a minor part of ethylene diamine. If desired, a small percentage 15 of morpholine may be included in such an anti-freeze agent. I have found, however, that the employment of methyl Cellosolve as an anti-freeze agent substantially aggravates the tendency toward the formation of heavy deleterious sludge, 20 both in the form of sludge suspension and in the form of sludge deposit. When even a small percentage of ethylene diamine is employed, either with water alone or with water and an anti-freeze agent such as methyl Cellosolve, the 25 sludge suspension is thinner and the sludge deposit more capable of flowing.

The present invention affords improved refrigerating systems of this general character in which the parts of the refrigerant circuit are arranged 30 to permit the efficient operation of the system either with an aqueous refrigerant comprising substantially pure water or a solution of an anti-freeze agent in water. Such a system is arranged so that sludge which has collected in the cooler 35 may be broken up so that the mercury returns to its normal state, thereby preventing the collection of a substantial quantity of deleterious sludge in the system and thus substantially avoiding the disadvantages described above.

A further aspect of the present invention relates to the arrangement of the cooler and associated piping to facilitate the vaporization of the refrigerant at a low pressure, such an arrangement being especially advantageous when an anti-freeze agent is employed which tends to impede vaporization. For example, during operation of the system, when methyl Cellosolve is employed as the anti-freeze agent, the proportion of the methyl Cellosolve at the surface of the liquid body in the cooler tends to be somewhat greater than in the remaining portion of that body and this layer of stronger solution does not vaporize as readily as a mixture having an average concentration of the methyl Cellosolve.

- The present invention affords arrangements of piping to cause agitation of the solution in the cooler, thus tending to cause the solution to be more uniform and aiding vaporization. Such an arrangement may also be conveniently employed to permit the cooler or evaporator and the water condenser to be near the same level so that the system may be compactly installed in a refrigerator casing of conventional height.
- 10 A further feature of the present invention relates to the provision of a chamber associated with an interstage cooler of the type disclosed in my prior United States Patent No. 1,756,802, to facilitate the collection of condensed mercury in this portion of the system and to direct the same to the trap assembly associated with the cooler and to the purger, which is effective in exhausting non-condensable gases from the system.
- 15 In order to break up sludge, which sometimes appears in a system of this character, a drum may be arranged to receive sludge which has collected in the cooler, this drum being connected to one of the aspirators, as the first-stage aspirator, so that the volatile refrigerant may be drawn from the 20 sludge, the mercury being dried to cause it to coalesce, whereupon it may drain to the lower part of the system. Preferably the trap connecting this drum to the cooler may be provided by a pipe of relatively large cross section to permit the 25 flow of the sludge to the drum under a moderate liquid head.
- Such a drum and the associated piping may also be arranged to prevent freezing to a seriously objectionable extent of the refrigerant returning 30 from the refrigerant condenser to the cooler or evaporator. Thus when freezing does occur in this portion of the system, the returning solution is directed into the drum and a portion of the pumping effect of the propellant is diverted to 35 cause the withdrawal of vapor from the drum. Accordingly there is less tendency to draw vapor from the cooler, and the temperature of the latter automatically tends to rise so that ice which has 40 formed in piping connecting the condenser to the cooler may melt.
- 45 The drum is also advantageous since it may involve the automatic maintenance of the boiler pressure within relatively close limits, despite a considerable variation in the amount of heat being supplied to the boiler, such an arrangement permitting the input of a surplus quantity of heat 50 without causing liquid mercury to rise into parts of the system where it would be undesirable.
- 55 The arrangement of the piping associated with the cooler may permit the returning condensate to be sprayed onto the surface of the liquid body in the cooler, thus breaking up the cold relatively less volatile layer which tends to collect at the surface of the liquid body. Associated with this piping 60 may be suitable means to introduce the returning condensate into the cooler in such a manner as to break up the cold layer even if freezing occurs in the piping through which the condensate is preferably supplied to spray onto the liquid surface.
- 65 The arrangement of this piping and the associated parts of the system may be such that the height of the liquid column which balances the 70 difference between the cooler and condenser pressures is automatically varied in accordance with variations in the pressure differential between the cooler and the condenser. The piping through which the condensate is supplied to the cooler may be combined with the means to receive sludge from the cooler and to supply the same to the drum where the mercury and refrigerant separate

and where vaporization of the refrigerant occurs if the refrigerant cannot flow to the cooler from the condenser due to the freezing of refrigerant in the piping between these parts of the system.

In the accompanying drawings:

Fig. 1 shows somewhat diagrammatically the arrangement of a refrigerating system employing a heavy high boiling point propellant, such as mercury, and an aqueous refrigerant, and exemplifying the novel features of the present invention:

Fig. 2 is an elevational view of the first stage aspirator and funnel assembly;

Fig. 3 is a horizontal section of the same indicated by line 3—3 of Fig. 2;

Fig. 11 is a detail view, partly in elevation and partly in section, of a portion of the system; and

Fig. 12 is a view similar to Fig. 6, but showing an optional trap assembly.

A system of this type may comprise a boiler 1 having a suitable heating element 2, such as a gas burner, provided with a draft-inducing flue 3 through which exhaust gases are vented. Mercury vapor passes from the boiler 1 through a riser pipe 5 to branches 5^a and 5^b which are connected respectively to the first and second stage aspirators. The first stage aspirator may comprise a nozzle 6 (Figs. 2 and 3) from which mercury vapor passes at relatively high velocity into a mixing chamber 7. The latter is connected by a vapor duct 8 to the cooler or evaporator 11. The latter may contain a body of liquid refrigerant, such as water, and a suitable anti-freeze ingredient. Vapor is drawn through the pipe 8 to the mixing chamber 7 and the mixed propellant and refrigerant vapors pass into the funnel 12, where the refrigerant is compressed and the mercury is condensed. The funnel preferably may have proportions of the order shown in Fig. 3, this advantageous form of funnel being more fully disclosed in my copending application Serial No. 177,489, filed December 2, 1937. The condensed mercury flows from the lower end of the funnel 12 into a drain 14, while the vapors pass into a pipe coil or loop 16 which is provided with cooling fins and forms an interstage cooler.

The latter is connected to an interstage drum or chamber 19 which has a substantially larger cross section than the interstage cooler pipe 16, so that the velocity of the vapor flowing through the drum is reduced, thus enhancing the tendency of condensed mercury particles to settle and collect at the lower part of the drum. The drum 19 may conveniently be provided with a bottom wall which inclines upwardly from its opposite sides to an intermediate ridge. Part of the condensed mercury collecting on this lower wall of the drum is directed to the pipe 20, while the remainder of the condensed mercury flows into the duct 21 which receives the refrigerant

vapor. The pipe 20 contains a suitable body of liquid mercury forming a trap to preclude the flow of vapor from the drum through this pipe, the end of the pipe being connected to the drain 14, so that mercury from this pipe may overflow into the drain and to parts of the system that will be described.

The compressed and cooled refrigerant vapor passes from the pipe 21 into the second stage mixing chamber 22 (Fig. 5) into which a stream of mercury flows at high velocity from the nozzle 23. This propellant stream is effective in causing further compression of the refrigerant vapor in the second stage funnel 25. A drain 27 receives condensed mercury from the funnel 25 and from the drain 14.

The first stage funnel 12 and the second stage funnel 25 preferably are provided with cooling fins 13 and 13^a, respectively, being disposed in jackets 12^a and 25^a which are connected respectively by ducts 12^b and 25^b to condensers or heat dissipators 12^c and 25^c. Each of the jackets may contain a body of liquid coolant, such as alcohol, which may be vaporized by the heat of the corresponding funnel, the vapor rising to the corresponding condenser 12^c or 25^c and the condensate draining back from each condenser to the corresponding jacket. Preferably the jackets and condensers may be evacuated before operation of the apparatus is started, so that the coolant vaporizes and condenses at a lower temperature than would be the case were these parts of the system at atmospheric pressure when the system was not in operation.

The compressed refrigerant vapor passes upwardly from the funnel 25 through the duct 29 to the refrigerant condenser 30. In practice a portion of the pipe 29 may be arranged in heat transfer relation to a warm part such as the riser branch 5^a or the interstage cooler 16 and the pipe may be provided with a plurality of internal protuberances or fins. Such fins may have openings therein to prevent pocketing of condensed mercury. The arrangement of the pipe 29 in this manner substantially prevents mercury from passing into the refrigerant condenser 30 and accordingly reduces the quantity of sludge formed by the condensate passing from the condenser back to the cooler 11. The condenser 30 may be of any suitable form, being either air cooled or water cooled, as desired. For example, this condenser might be of the type disclosed in my copending application Serial No. 171,647, filed October 29, 1937. As shown herein for purposes of illustration, the condenser 30 comprises a conventional pipe assembly with cooling fins 31.

A chamber or drum 32 preferably is located at the end of condenser 30 which is remote from the pipe 29. A pipe 44 has an open end communicating with this chamber and receives non-condensable gases therefrom.

The lower portion of the condenser chamber 32 is connected to a drain or return pipe 34 through which condensed refrigerant may pass on its way back to the cooler. Especially when an anti-freeze agent is employed which tends to collect in a stronger solution at the upper part of the body of liquid refrigerant in the cooler, I preferably provide means to introduce the freshly condensed weak refrigerant into the cooler so that it tends to break up or dilute the strong solution. For this purpose the pipe 34 may have its lower end connected to an upwardly extending duct 35 (Fig. 6). The upper end 75 of the latter is connected to a tube 36 of small

diameter, which communicates with the interior of the cooler 11 above the surface of the liquid contained therein.

The lower parts of the pipe 34 and of the duct 35 form a trap A containing mercury which, during normal operation, stands higher in leg 35 (Fig. 7). As condensed refrigerant collects above the mercury in the pipe 34, it depresses the mercury sufficiently to permit the liquid refrigerant to rise through the mercury column in the other leg of trap A, i. e., to pass into the upper part of duct 35. Since the temperature of the returning refrigerant is high relative to the temperature of the cooler, and since the pressure in the cooler is low, some vaporization of the refrigerant occurs in duct 35. Accordingly, the refrigerant passes through the tube 36 in the form of separate slugs or separate bodies of liquid, which are propelled by bodies of vaporized refrigerant. Thus the returning refrigerant may be sprayed onto the surface of the liquid refrigerant in cooler 11. Accordingly, the stronger anti-freeze solution, which tends to collect at the top of the liquid body, is diluted and agitated, so that vaporization can more readily take place at the surface of the liquid body.

Furthermore, I have found that, for example, when water alone is employed as a refrigerant, a thin cold film tends to form at the surface of the liquid body in the cooler. This film has a temperature lower than the mean temperature of the cooler, the refrigerant at the surface accordingly being less volatile than the remainder of the liquid body. The arrangement of the tube 36 to spatter slugs of refrigerant causes this cold film to be broken up and accordingly this arrangement is also advantageous in enhancing the cooler efficiency even when an anti-freeze agent is not used.

Under certain conditions, particularly due to the restricted diameter of tube 36, the returning refrigerant may freeze in this tube so that the condensed refrigerant cannot return to the evaporator 11 in the manner which has been described. To provide for such an eventuality, I provide means which permits the by-passing of the refrigerant to the cooler. For this purpose, the lower end of pipe 34 is connected to an inclined tube 40, the upper end of which has a vertical continuation 42 that may extend above the liquid level in the cooler and have a connection with a downwardly extending pipe 43 which is connected to a duct 44, which also serves as a drain. The upper end of duct 44 communicates with the lower part of the cooler 11, and stray propellant particles may drain from the cooler through this duct. When freezing occurs in the tube 36, liquid refrigerant will depress the mercury at the juncture of pipes 34 and 40, so that the refrigerant may rise in the duct portion 42 and pass into the portion 43 flowing from the latter into the drain 44. The returning refrigerant, which may be a relatively weak solution, passes into the stronger solution in duct 44 before reaching the cooler. I have found that the introduction of the weak solution in this manner tends to prevent freezing and also aids in breaking up the cold film at the surface of the liquid body, so that this arrangement, while particularly advantageous when an anti-freeze agent is employed in the refrigerant, may also be used when a refrigerant such as pure water is used. In fact, such an arrangement gives an effect comparable to that afforded when the refrigerant is spattered from the tube 36 into the cooler.

The lower part of duct 44 provides a shallow

trap communicating with a drum 50 (Fig. 11). The duct 44 preferably has a relatively large diameter. A trap 51 connects this shallow trap to the second stage mixing chamber 22, while a drain 49 connects the first stage mixing chamber to the upper part of drum 50.

A drain 55 extends from the bottom of the drum to a trap 56, the opposite leg of which is connected to a duct 57, while the lower end of the latter communicates with the boiler 1. The drain pipe 27 for the second stage funnel 25 is connected to a small chamber 60 into which the lower end of inclined pipe 40 extends, and an upwardly inclined duct 61 extends from the chamber 60 to the chamber 64 of the purger assembly 63 (Fig. 8). This assembly is of the type disclosed in my co-pending application Serial No. 167,402, filed October 5, 1937. A drop tube 65 of restricted internal diameter extends downwardly from the chamber 64, which receives gas through pipe 44. Bodies or globules of liquid propellant spilling over from the duct 61 entrap bodies of non-condensable gas in the tube 65, compressing the gas as they flow downwardly through the tube. The lower end of the tube 65 is immersed in a body of liquid propellant in the well 67, the upper surface of this liquid propellant being exposed to the atmosphere.

A return duct 69 is disposed about the tube 65 and is connected to the pipe 57, there being a very small pressure equalizing vent 70 connecting the upper part of duct 69 and the chamber 64. A deflector 68 prevents gas from rising into the duct 69 from the open lower end of tube 65, such a deflector being more fully disclosed in the co-pending application of Raymond W. Tibbets, Serial No. 168,958, filed October 14, 1937. The arrangement of the spill-over connection between tube 61 and chamber 64 determines the levels of the propellant in other parts of the system, as will be more fully described, the level of this connection being indicated by the dot and dash line in Fig. 1. The condensed propellant received from drains 20, 14 and 27 passes to the receptacle 60 and from the latter may pass to the spill-over connection, thus being received by the purger. From the purger the liquid propellant flows through pipe 57 back to the boiler, the height of the mercury in pipes 57 and 69 being sufficient to balance the boiler pressure.

The pipes 34 and 35 form a trap A, while the pipes 61 and 40 also are included in a trap B, but the leg of this trap provided by pipe 40 has branches afforded by the pipes 34 and 35 of trap A, while pipe 42 may also be regarded as providing another branch of this leg.

Trap B is constantly receiving mercury from pipe 27 during normal operation of the system, and the spill-over connection between pipe 61 and chamber 64 definitely limits the height of the mercury in pipe 27. Thus a mercury column of constant height is automatically maintained in leg 61 of trap B, while the total static pressure in this leg of this trap is provided by this mercury column and the condenser pressure thereabove. Such a total static pressure is balanced on the opposite side of the trap by components afforded not only by the mercury in pipe 40 but by the liquid heads in the respective branches of this leg 70 of the trap B and by the respective pressures thereabove. The liquid heads in the respective branches may be provided by columns of mercury or of mercury and liquid refrigerant.

As a practical matter, the pressures above the 75 branches of leg 40 do not exceed the condenser

pressure which is always imposed on the mercury column in leg 61 of trap B, so that the level of the spill-over connection determines the minimum height of the liquid in each of the branches 34, 35 and 42 of leg 40, this level being indicated by the dot and dash line of Fig. 1. When the pressures above the columns in ducts 35 and 42 are less than the condenser pressure, the liquid levels may rise above the level of the dotted line in Fig. 1. In either duct 34, 35 or 42 the level may 10 rise above the level of the dotted line when liquid refrigerant displaces propellant.

Assuming that the system is not in operation and that only mercury is contained in trap A, the level of the mercury in pipes 34 and 35 will 15 be the same as that in pipe 61 of trap B, such a level ordinarily being even with the spill-over connection and being indicated by the dot and dash line of Fig. 1, and being shown in Fig. 6.

If the system is then started in operation, the 20 pressure of the cooler falls below that of the condenser. Obviously, total pressures at opposite sides of trap A must be equal and mercury rises in pipe 35 as the pressure of the cooler falls relative to that of the condenser, while the mercury 25 in pipe 34 remains at the level of the spill-over connection. The additional mercury received under such conditions by pipe 35 comes from the lower part of trap B which is receiving mercury 30 from drain 27.

If the pressure difference between the cooler and condenser then falls, the liquid head in pipe 35 is automatically reduced and mercury is received by the lower part of trap B, causing mercury to overflow at the spill-over connection. 35

When the mercury columns are in the condition just described, liquid refrigerant may be received by pipe 34. The refrigerant piles up above the mercury in that pipe and, assuming conditions otherwise remain unchanged, this refrigerant 40 displaces mercury in the pipe 34, this mercury passing into the lower part of trap B and causing mercury to overflow at the spill-over connection between pipe 61 and chamber 64. The refrigerant may thus continue to pile up in pipe 34 45 until it depresses the mercury sufficiently to permit some of the refrigerant to rise into the opposite leg 35 of the trap. The refrigerant passing into pipe 35 rises to the top of the mercury in that pipe, displacing some of the mercury in that 50 leg of trap A, this mercury being received by the lower part of trap B. The refrigerant returns from pipe 35 to the cooler through tube 36 in the manner which has been described. It is thus evident that under average operating conditions 55 the liquid column in pipe 34 may consist almost entirely of refrigerant, while the column in pipe 35 may ordinarily consist of both mercury and refrigerant, such a condition being indicated in Fig. 7.

It is evident that when the liquid heads are 60 unchanged but mercury replaces refrigerant in one of the liquid columns of trap A, the height of the column will be reduced, since mercury is much heavier than the refrigerant which it replaces. Conversely, when refrigerant replaces mercury to provide the same liquid head, the liquid level will rise substantially.

It is now evident that the liquid head in pipe 61 equals that in pipe 34 plus that in pipe 40 70 below its connection to pipe 34, since the upper parts of pipes 61 and 34 intercommunicate through the condenser. The liquid level in pipe 34 is higher than the spill-over connection, however, if pipe 34 contains liquid refrigerant. The 75

liquid head in pipe 35 is automatically adjusted to compensate for changes in the pressure difference between the cooler and condenser, the difference between the liquid heads in legs 34 and 5 35 of trap A tending to equal this pressure difference.

The liquid column in pipe 42 is similarly automatically controlled, the liquid heads in that pipe sometimes differing from that in pipe 35 10 due to minor differences between the vapor pressures in the upper parts of these pipes.

Very important advantages are afforded by such an arrangement over the return piping arrangements which have previously been used in 15 systems of this character. Heretofore the propellant-containing trap in the return piping has had to contain sufficient mercury to balance the maximum pressure differential between the cooler and the condenser. Accordingly, when 20 this differential was not large, a relatively high column of the lighter refrigerant was required in the leg of the trap connected to the condenser in order to balance this quantity of heavier mercury so that the refrigerant could pass through 25 the trap and into the cooler. Accordingly the condenser had to be at a substantial distance above the cooler and the height of the system was substantially greater than is required by the present arrangement.

30 Assuming there is no refrigerant in pipe 34 of the present system, the height of the mercury column above the juncture of pipes 34 and 35 is independent of pressure changes in the system, and by proper design this height can be made 35 very small; thus only a relatively short column of refrigerant may be needed to depress the mercury sufficiently to permit refrigerant to pass to the cooler. This arrangement permits the height of the refrigerant column in pipe 34 to be substantially constant and to be determined by 40 the position of the juncture of the legs 34 and 35 of trap A relative to the height of the spill-over connection between ducts 61 and 63. Consequently a system of this character can be compactly arranged in a refrigerator housing of 45 moderate height. The attainment of this important result is further materially aided by the arrangement of the downwardly extending pipe 43 between the upper end of pipe 42 and the connection to pipe 44, this arrangement permitting 50 the cooler to be disposed a number of inches lower than would be the case were the upper part of pipe 42 directly connected to the pipe 44 below the cooler by a conventional horizontal connection.

55 Any mercury received by the refrigerant condenser flows downwardly through the duct 34 to the trap A at the lower part of this duct. Mercury particles which pass into the cooler 11 drain downwardly into the shallow trap provided by duct 44, piling up until mercury overflows into the drum 50. The latter also receives condensed mercury from the first and second stage mixing chambers. Obviously when the boiler pressure is normal, the mercury column in pipe 55 may have its upper surface below the drum 50. Accordingly mercury received by the drum passes into this pipe, returning through the trap 56 and the lower part of duct 57 to the boiler. It is thus evident that mercury is returned to the boiler from the drum 50 and through the upper portion of duct 57 which receives the mercury supplied to the purger.

When heat is supplied by burner 2 at an abnormally high rate, thus tending to cause the

boiler pressure to rise, mercury may rise into the drum 50. Due to the relatively large horizontal size of the latter, a substantial quantity of mercury is required in order to increase the mercury level appreciably in this drum. Thus 5 as the mercury rises in the drum, the mercury level falls in the boiler, increasing the effective static head of the mercury column which balances the boiler pressure. If this action continues, the mercury level in the boiler falls sufficiently so that a portion of the firebox 170 (Fig. 10) is uncovered and the quantity of liquid mercury in contact with the firebox is thus reduced. Thereupon the boiler becomes less efficient so that the actual amount of mercury vapor supplied to the aspirator nozzles is not materially increased despite the higher rate of gas supply to the burner. This arrangement furthermore prevents mercury from rising under such conditions into parts of the system where it would be undesirable.

The drum 50 not only has this function of aiding the automatic regulation of the boiler, but it also is effective in automatically reducing the rate of evaporation in the cooler when the refrigerant freezes in the pipe 44. When the tube 36 and the upper part of pipe 44 are both blocked by frozen refrigerant, the condensed refrigerant can no longer pass to the cooler. Under these conditions, the refrigerant flows through the 30 ducts 42 and 43 into the lower part of pipe 44, displacing the mercury in the latter and passing into the drum 50. The upper part of this drum is connected by the pipe 49 to the low pressure 35 portion of the refrigerant circuit, i. e., to the first stage mixing chamber. Accordingly, refrigerant vapor is then withdrawn from the drum 50 as well as from the cooler 11, so that part of the pumping effect of the mercury jet is being employed in pumping vapor from drum 50. Accordingly the rate of evaporation in cooler 11 is reduced so that its temperature rises, causing 40 the ice which has formed in the pipes 36 and 44 to melt.

The drum 50 also has a third function when 45 sludge collects in the cooler. As has been explained, it is desirable to employ an anti-freeze agent with the water to reduce the temperature which may be obtained in the cooler without resulting in freezing of the refrigerant. For this purpose an anti-freeze ingredient such, for example, as methyl Cellosolve or ethylene diamine, or mixtures of methyl Cellosolve and ethylene diamine may be employed in solution in the water.

55 Since, however, ethylene diamine, if used in substantial quantities, tends to attack the walls of a conventional steel system, I prefer, in such a system, to use methyl Cellosolve alone with water or with a very small admixture of ethylene diamine, i. e., the latter not being over 5% of the weight of the solution.

The use of methyl Cellosolve, as commercially obtained, for an anti-freeze agent, however, increases the tendency of deleterious sludge to 60 form in the system. When the mercury particles pass into the refrigerant condenser, some thin sludge suspension may form, this sludge consisting of the refrigerant and suspended mercury particles and passing through the mercury trap at the lower part of duct 34 and into the cooler. Also, under certain conditions some of the mercury from the first stage nozzle may pass through the pipe 8 into the cooler 11, causing 70 the formation of sludge. The sludge may even- 75

tually form a deposit on the lower walls of the cooler, which has the consistency of thick mud. As shown in Fig. 13, the cooler 11 preferably is provided with lower walls which slope downwardly at a substantial angle toward the pipe 44, so that the heavy mud-like deposit can drain into pipe 44 which itself is of relatively large diameter to permit movement of the "mud".

While for convenience of illustration, the lower part of pipe 44 is shown in the accompanying drawings as having a substantial length, it is practically desirable to make this portion of pipe 44 relatively short; thus requiring less mercury for this portion of the system. A reduction of the length of this pipe saves mercury not only directly due to the reduced length but also because the pipe can then be made of smaller diameter and yet not afford an unduly high resistance to the movement of sludge to the drum 50.

With the arrangement disclosed herein, heavy mud-like sludge piling up on the mercury in the shallow trap formed by pipe 44 depresses the mercury in this trap and passes into the drum 50. The latter is connected to the first stage mixing chamber by the duct 49. Accordingly, under these conditions the more volatile portion of the heavy sludge, i. e., the refrigerant, is drawn into the first stage mixing chamber and the mercury residue flows downwardly into the drain 55.

Preferably various warm portions of the system such as the mixing chambers and aspirator nozzles, the stack 3, the riser 5 and its branches, and the boiler may be enclosed in a casing 100 filled with discrete insulating materials, such as Cel-o-cel. The mixing chamber heads may conveniently be supported upon this casing, as shown in Fig. 1, and U-shaped brackets 95 (Figs. 2, 3, 4 and 5) may be connected to these heads to support the nozzles 6 and 23 in accurate concentric alignment with the corresponding funnels. For this purpose bars 97 of metal of low heat conductivity, such as nichrome, may be adjustably connected to the eight portions of the brackets.

If desired, the pipes 35 and 36 shown in Fig. 1 may be omitted and the system be arranged so that the refrigerant always returns to the cooler through the pipe 42. Such an alternative arrangement is illustrated in Fig. 12 and the operation of the system with this arrangement is similar to that which has been described as taking place when the refrigerant in tube 36 of Fig. 6 becomes frozen.

In the operation of a system of this character, it is obvious that the mercury is boiled in the vaporizer 1, the vapor passing upwardly through riser 5 and its branches 5^a and 5^b to the aspirator nozzles. Refrigerant vapor is drawn from the liquid body in cooler 11 through the duct 8 into the first stage funnel, being there compressed and pumped into the interstage cooler 16, while condensed mercury is received from the funnel by drain 14. Condensing mercury particles settle on the bottom wall of chamber 19, a portion of this mercury being directed through pipe 20 to drain 14 and the remainder of the mercury passing into the vapor duct 21 and from the latter through the trap 51 and into the trap provided by the pipe 44. The refrigerant vapor from the duct 21 is further compressed in the second stage funnel 25 and pumped into the condenser 30 from which the condensed refrigerant passes into the pipe 34.

Non-condensable gases which are heavier than the refrigerant vapor pass into the drum 32 and are received by the pipe 44 which supplies them to the purger where they are compressed and exhausted to the atmosphere. The mercury received by the pipe 20 and by the drains 14 and 27, which are connected to the first and second stage funnels, respectively, may pass into the purger, there being effective in compressing the non-condensable gases, or this mercury may temporarily pass to the trap assembly associated with the cooler, for example, to provide additional mercury for liquid heads in trap A as has been described. Mercury from the second stage mixing chamber 22 passes through pipe 51 and into pipe 44. This mercury may overflow into drum 50 and pass from the same through pipe 55 into the return pipe 57 which also receives the mercury from the purger. Mercury from the first stage mixing chamber is also received by drum 50 and may ordinarily drain into pipes 55 and 57.

Mercury columns in pipes 55 and 57 and in the return duct 69 of the purger automatically are maintained at heights which balance the boiler pressure. Under normal operating conditions refrigerant from pipe 34 depresses mercury in the trap A at the lower end of this pipe, so that the refrigerant rises to the duct 35 where partial vaporization thereof may occur so that slugs of refrigerant are spattered onto the surface of the liquid in cooler 11. Should freezing occur in this portion of the system, i. e., in the tube 36, the mercury at the lower end of duct 34 will be further depressed so that the refrigerant will rise into pipe 42, being supplied from the latter through pipe 43 to the duct 44 and thence to the cooler. Should both the tube 36 and the upper part of pipe 44 become choked with frozen refrigerant, the refrigerant from pipe 34 will depress the mercury in the trap 44 so that the refrigerant will find its way through this trap into the drum 50, being pumped from the latter to the first stage mixing chamber through the drain 49 so that the first stage aspirator is then effective in pumping refrigerant vapor from the drum 50 as well as from the cooler 11. Accordingly the rate of evaporation in the latter is reduced and the temperature of the same rises so that the ice in its inlet pipes may melt.

Should the boiler temperature tend to be inordinately high, the mercury column in pipe 55 will rise until mercury spills over into the drum 50, whereupon the mercury level in the boiler may start falling, thus causing an increase in the height of the mercury column which balances the boiler pressure. If the mercury continues, however, to rise in the drum 50, the boiler may become partially denuded so that a portion of the firebox is uncovered and the efficiency of the boiler is automatically decreased.

Should a substantial sludge deposit collect in the lower part of cooler 11, some of the sludge will find its way through the trap provided by pipe 44 into the drum 50. Here the refrigerant is separated from the mercury particles, the refrigerant being vaporized and being drawn through the pipe 49 and the mercury coalescing into its normal state and being received by the return pipe 55. While the sludge in which the finely dispersed mercury particles are included is disadvantageous in refrigerating systems of the character described, this sludge has unusual properties that I believe will be advantageous in other fields.

- It is evident that the present invention permits a compact system to be provided to employ mercury vapor to pump refrigerant, while permitting low temperatures to be obtained in the cooler.
- 5 The arrangement of the piping associated with the cooler not only permits the cooler to be near the level of the refrigerant condenser, if desired, but also facilitates vaporization of the anti-freeze solution despite the tendency of a stronger
- 10 solution to collect at the top of the liquid body in the cooler and despite the less volatile character of the anti-freeze agent. This arrangement of piping also automatically permits normal operation of the system automatically to be resumed
- 15 if freezing occurs in the inlet piping adjoining the cooler. Furthermore, the assembly permits the automatic separation of mercury from sludge which may collect in the lower part of the cooler, thus avoiding clogging of pipes or the like. The
- 20 arrangement of the drum 50 and associated parts of the system also permits a system of this character to be provided which will not be sensitive to abnormally high boiler temperatures. The arrangement of the separating chamber 19 permits adequate replenishment of the mercury supply in the trap assembly associated with the cooler and with the drum 50, and also assures the supply of some mercury to the purger under all operating conditions.
- 25 It should be understood that the present disclosure is for the purpose of illustration only and that this invention includes all modifications and equivalents which fall within the scope of the appended claims.
- 30 I claim:
1. Refrigerating apparatus of the class described comprising a propellant circuit and a refrigerant circuit, said circuits having a common part where propellant vapor pumps and compresses refrigerant vapor and where the propellant vapor is condensed, said propellant circuit also including a boiler, a duct supplying propellant vapor from the boiler to said common part, and a return pipe directing condensed propellant from said common part to the boiler and containing liquid propellant to balance the boiler pressure, said refrigerant circuit also including a refrigerant condenser and a cooler, and a drum disposed between said common part and said return pipe, said drum having a cross-sectional size substantially greater than that of the return pipe, whereby, when the boiler pressure rises, the upper part of the liquid column is received in the drum and the height of the mercury column in the boiler is decreased in response to further increase in temperature of the boiler, so that the boiler pressure may be automatically maintained within rather closely predetermined limits despite variations in the amount of heat being supplied to the boiler.
- 35 2. Refrigerating apparatus of the class described comprising a propellant circuit and a refrigerant circuit, said circuits having a part in common where propellant vapor pumps and compresses refrigerant vapor and where the propellant vapor is condensed, said propellant circuit also including a boiler, a duct supplying propellant vapor from the boiler to said common part, and a return pipe directing condensed propellant from said common part to the boiler and containing a column of liquid propellant to balance the boiler pressure, said refrigerant circuit also including a refrigerant condenser and a cooler, and a drum disposed between said common part and said return pipe, said drum having
- 40 a cross-sectional size substantially greater than that of the return pipe, whereby, when the boiler pressure rises, the upper part of the liquid column is received in the drum and the height of the mercury column in the boiler is decreased, so that the boiler pressure may be automatically maintained within rather close predetermined limits despite variations in the amount of heat being supplied to the boiler, a trap containing a body of the liquid propellant and having legs communicating respectively with the drum and cooler, the refrigerant circuit including a duct receiving condensed refrigerant from the refrigerant condenser and supplying the same to the leg of the trap which is connected to the cooler, whereby when the condensed refrigerant freezes between the connection of the duct to said last-named leg and the cooler, the condensed refrigerant passes into the drum and is evaporated and pumped out of the drum by the propellant vapor passing through said common part, so that evaporation in the cooler is retarded and the temperature thereof tends to rise causing melting of refrigerant in said leg of the trap, and whereby sludge may pass from the cooler to the drum and refrigerant be drawn from the sludge.
- 45 3. Refrigerating apparatus comprising a refrigerant circuit including a cooler and a condenser, means to pump refrigerant about said circuit and to cause a low pressure in the cooler and a higher pressure in the condenser, said cooler normally containing a body of liquid refrigerant, a cold, relatively less volatile layer of said refrigerant tending to collect at the surface of the body, the refrigerant circuit being arranged to direct condensed refrigerant from the condenser into the cooler so that the liquid in said layer is agitated and mixed with more volatile refrigerant, whereby its volatility is increased and the cooler efficiency enhanced.
- 50 4. Refrigerating apparatus comprising a refrigerant circuit including a cooler and a condenser, means to pump refrigerant about said circuit and to cause a low pressure in the cooler and a higher pressure in the condenser, said cooler normally containing a body of liquid refrigerant, a cold, relatively less volatile layer of said refrigerant tending to collect at the surface of the body, the refrigerant circuit being arranged to spray condensed refrigerant from the condenser onto the surface of said liquid body, thereby impeding the formation of said layer.
- 55 5. Refrigerating apparatus comprising a refrigerant circuit including a cooler and a condenser, means to pump refrigerant about said circuit and to cause a low pressure in the cooler and a higher pressure in the condenser, said cooler containing a liquid body of refrigerant which includes a more volatile constituent and a less volatile constituent, the less volatile constituent tending to collect more strongly in a cold layer of liquid at the upper surface of the liquid body, said refrigerant circuit being arranged to direct condensed refrigerant from the condenser into the cooler so that the liquid in said layer is agitated and mixed with the more volatile refrigerant, whereby its volatility is increased and the cooler efficiency enhanced.
- 60 6. Refrigerating apparatus of the class described, comprising a refrigerant circuit including a cooler and a condenser, said cooler containing a body of liquid refrigerant, means to pump refrigerant through said circuit, the circuit including a return duct receiving condensed refrigerant from the condenser, a trap having one

- leg provided by said duct, a tube connecting the upper part of the other leg of the trap to the cooler above the surface of said liquid body, the trap being arranged so that when refrigerant passes through the same, some of the refrigerant in the last-named leg of the trap is vaporized to force slugs of liquid refrigerant from the tube onto the surface of said liquid body.
7. Refrigerating apparatus comprising a refrigerant circuit having a low pressure portion including a cooler and having a high pressure portion including a condenser, a propellant circuit including a vaporizer and a part in common with said refrigerant circuit wherein refrigerant vapor from the cooler is entrained in a stream of the propellant vapor from the vaporizer, said vaporizer containing a body of mercury, a return duct extending from the condenser to the cooler, said duct having a trap with a pressure balancing column of propellant in one leg, a section of the duct extending downwardly from said leg to a connection to the cooler below the latter, said cooler containing a body of liquid refrigerant comprising water and an anti-freeze agent in solution therewith, the solution tending to be stronger in the anti-freeze agent in a layer at the upper surface of the liquid body, the returning refrigerant received through said connection tending to break up said stronger layer, means connected to said trap automatically to vary the height of the pressure balancing column in response to changes in the pressure difference between the cooler and condenser, a chamber arranged to receive sludge from said connection, and a pipe connecting the chamber to the low pressure portion of said refrigerant circuit, whereby the refrigerant may be drawn from the sludge.
8. Refrigerating apparatus comprising a refrigerant circuit including a cooler and a condenser, a propellant circuit including a vaporizer and a part in common with said refrigerant circuit wherein refrigerant vapor from the cooler is entrained in a stream of the propellant vapor from the vaporizer, said vaporizer containing a body of mercury, said refrigerant circuit including a return pipe extending downwardly from the condenser, said pipe providing one leg of a trap, the opposite leg of the trap containing a pressure-balancing column of propellant and extending upwardly, the top of the last-named leg communicating with a tube which is connected to the cooler above the surface of the liquid refrigerant contained therein, whereby slugs of refrigerant may be emitted from the tube onto said surface, the lower end of the pipe being connected to a duct containing a second pressure-balancing column, a second duct connected to the bottom of the cooler, a downwardly extending continuation of the first duct having a connection with the second duct substantially below the cooler, whereby, when refrigerant freezes in the tube, the returning refrigerant may enter the cooler through said ducts.
9. Refrigerating apparatus comprising a refrigerant circuit including a cooler and a condenser, a propellant circuit including a vaporizer and a part in common with said refrigerant circuit wherein refrigerant vapor from the cooler is entrained in a stream of the propellant vapor from the vaporizer, said vaporizer containing a body of mercury, a return duct extending from the condenser to the cooler, said duct having a trap with a pressure-balancing column of propellant in one leg, a section of the duct extend-
- ing downwardly from said leg to a connection to the cooler below the latter, and means connected to said trap automatically to vary the height of the pressure-balancing column in response to changes in the pressure difference between the cooler and condenser.
10. Refrigerating apparatus comprising a refrigerant circuit including a cooler and a condenser, means for pumping the refrigerant from the cooler to the condenser and to afford a low pressure in the former and a higher pressure in the latter, said circuit having a duct extending from the condenser to the cooler, said duct including a trap having a leg containing a column of liquid to balance the pressure difference between the cooler and condenser, the liquid refrigerant from the condenser piling up in the opposite leg of the trap so that it may have sufficient head to permit refrigerant to rise through said column of liquid, and means connected to the trap and to the condenser automatically effective to vary the height of said column in response to variations in said pressure difference.
11. Refrigerating apparatus comprising a refrigerant circuit including a cooler and a condenser, means for pumping the refrigerant from the cooler to the condenser and to afford a relatively low pressure in the former and a higher pressure in the latter, said circuit having a duct extending from the condenser to the cooler, said duct including a trap having a leg containing a column of liquid to balance the pressure difference between the cooler and condenser, the liquid refrigerant from the condenser piling up in the opposite leg of the trap so that it may have sufficient head to permit refrigerant to rise through said column of liquid, a second trap containing a body of the liquid and having one leg connected to the lower part of the first-named trap, the second trap having its opposite leg provided with a spill-over connection determining the level of liquid in that leg of the trap, the last-named leg of the second trap being connected to the condenser and subject to the condenser pressure, said system being arranged to direct liquid into the lower part of the second trap, whereby the liquid column in said first-named trap may have a head above the spill-over connection which is automatically varied to compensate for changes in the pressure difference between the cooler and condenser.
12. A system of the class described comprising a heavy liquid circuit and a light liquid circuit having two portions at different pressures, said last-named circuit including a trap having legs connected respectively to each of said portions, the leg connected to the low pressure portion containing a column of heavy liquid tending to balance pressure differences between said portions, the opposite leg containing a column of lighter liquid which may become high enough to permit some of the lighter liquid to leak through the trap and rise through the column of heavy liquid, said heavy liquid circuit including a trap having one leg connected to the lower part of the first-named trap and having its opposite leg provided with a spill-over connection, said connection communicating with the high pressure portion of the light liquid circuit, the heavy liquid rising from the second-named trap into said heavy liquid column in the first trap when the pressure difference between said portions rises and flowing from said first-named trap into the second trap when the pressure difference falls, whereby the height of said heavy

liquid column above the spill-over connection in the first trap is automatically adjusted in accordance with varying pressure differences between said portions.

- 5 13. Refrigerating apparatus comprising a refrigerant circuit including a condenser and a cooler, said cooler containing a body of relatively light refrigerant, a propellant circuit comprising a vaporizer and a part in common with the refrigerant circuit where propellant vapor is effective in drawing refrigerant vapor from the cooler, compressing the same, and pumping the same to the condenser, and where the propellant is condensed, said refrigerant circuit also including a duct extending from the condenser to the cooler, said duct having a trap with one leg connected to the cooler and containing a column of the propellant tending to balance the difference in pressure between the cooler and condenser, the propellant circuit having a trap receiving condensed propellant from said common part, said second-named trap having one leg connected to the lower portion of the first-named trap and having its opposite leg provided with a spill-over connection from which the propellant is returned to the vaporizer, the propellant column in the first-named trap being automatically adjusted in accordance with varying differences in pressure between the cooler and condenser, the liquid refrigerant in the other leg of the first-named trap piling up to leak through the trap and rise through said heavy liquid column and thus return to the cooler.

14. Refrigerating apparatus of the class described comprising a refrigerant circuit including a condenser and a cooler, a propellant circuit including a vaporizer and a part in common with the refrigerant circuit where the propellant draws refrigerant vapor from the cooler, compresses the vapor, and pumps the same to the condenser, a drain extending downwardly from the cooler and connected to the propellant circuit through which stray propellant may be returned to the propellant circuit, a duct extending from the condenser to a connection with said drain, said duct having a trap therein, a second trap having a leg connected to the lower part of the first-named trap and receiving condensed propellant from said common part of the circuits, the opposite leg of the second trap having a spill-over connection, the first-named trap having a leg containing a column of the propellant tending to balance the pressure difference between the cooler and condenser, the upper part of said leg being above the connection of the duct and drain, the duct having a section extending downwardly to its connection with said drain.

15. Refrigerating apparatus of the class described comprising a refrigerant circuit including a condenser and a cooler, a propellant circuit including a vaporizer and a part in common with the refrigerant circuit where the propellant draws refrigerant vapor from the cooler, compresses the vapor and pumps the same to the condenser, a drain extending downwardly from the cooler and connected to the propellant circuit through which stray propellant may be returned to the propellant circuit, a duct extending from the condenser to a connection with said drain, said duct having a trap therein, a second trap having a leg connected to the lower part of the first-named trap and receiving condensed propellant from said common part of the circuits, the opposite leg of the second trap

having a spill-over connection, the first-named trap having a leg containing a column of the propellant to balance the pressure difference between the cooler and condenser, the upper part of said leg being above the connection of the duct and drain, the duct having a section extending downwardly to the connection with said drain, the lower part of said duct section and the adjoining part of said drain providing a third trap containing propellant liquid, and means to supply said liquid from the common part of the circuits to said third trap.

16. Refrigerating apparatus of the class described comprising a propellant circuit and a refrigerant circuit, said circuits having common parts where propellant vapor pumps and compresses refrigerant vapor and where the propellant vapor condenses, said parts being in successive portions of the refrigerant circuit and in parallel portions of the propellant circuit, the refrigerant circuit also including a cooler, a condenser, an interstage cooler between said common parts, a pipe extending from the interstage cooler to the second of said common parts, and a receptacle in said pipe providing a portion of enlarged cross section where propellant particles may more readily collect, a trap receiving propellant from said common part, said trap having one leg provided with a spill-over connection, the opposite leg of said trap being connected to a trap in the refrigerant circuit between the condenser and the cooler, said last-named trap having one leg containing a pressure-balancing liquid column, said leg having its upper end connected with the cooler, the opposite leg of the trap normally containing condensed refrigerant which, when piling up in this leg of the trap, may pass through the trap, rising into the liquid column and return to the cooler, the height above the spill-over connection of said liquid column in the first-named leg of the trap being automatically varied in accordance with variations in differences between the cooler and condenser pressures, the liquid in said column being received from the first-named trap and the receptacle when the height of the column increases, and the liquid from the column displacing liquid in the first-named trap and causing some of the liquid from that trap to pass through the spill-over connection when the height of the column decreases.

17. Apparatus of the class described comprising a propellant circuit and a refrigerant circuit, said circuits having common parts where propellant vapor pumps and compresses refrigerant vapor and where the propellant vapor condenses, said parts being in successive portions of the refrigerant circuit and in parallel portions of the propellant circuit, the propellant circuit also including a boiler and return piping connecting said common parts to the boiler, the refrigerant circuit also including a cooler, a refrigerant condenser, an interstage cooler between said common parts and a pipe extending from the interstage cooler to the second of said common parts, a receptacle in said pipe providing a portion of enlarged cross section where propellant particles may more readily collect.

18. Apparatus of the class described comprising a propellant circuit and a refrigerant circuit, said circuits having common parts where propellant vapor pumps and compresses refrigerant vapor and where the propellant vapor condenses, said parts being in successive portions of the refrigerant circuit and in parallel portions of

the propellant circuit, the propellant circuit also including a boiler and return piping connecting said common parts to the boiler, the refrigerant circuit also including a cooler, a refrigerant condenser, an interstage cooler between said common parts, and a pipe extending from the interstage cooler to the second of said common parts, a receptacle in said pipe providing a portion of enlarged cross section where propellant particles may more readily collect, the refrigerant circuit also including a trap between the condenser and cooler, the trap being arranged to receive condensed propellant from said receptacle.

19. Apparatus of the class described comprising a propellant circuit and a refrigerant circuit, said circuits having common parts where propellant vapor pumps and compresses refrigerant vapor and where the propellant vapor condenses, said parts being in successive portions of the refrigerant circuit and in parallel portions of the propellant circuit, the propellant circuit also including a boiler and return piping connecting said common parts to the boiler, the refrigerant circuit also including a cooler, a refrigerant condenser, an interstage cooler between said common parts, and a pipe extending from the interstage cooler to the second of said common parts, a receptacle in said pipe providing a portion of enlarged cross section where propellant particles may more readily collect, the refrigerant circuit also including a trap between the condenser and cooler, the system having a purger receiving propellant liquid and arranged to pump non-condensable gases from the system, said receptacle having connections arranged to assure part of the propellant draining from the trap and a part thereof draining to the purger.

20. Refrigerating apparatus of the class described comprising a refrigerant circuit including a cooler, a condenser and means to pump refrigerant about said circuit, said circuit also including a return duct extending from the condenser to the cooler, said duct having a trap

therein arranged so that a column of liquid refrigerant may pile up in one leg of the trap to overbalance a column of liquid in the opposite leg thereof and may thus pass through the trap, the last-named leg of the trap extending upwardly to a region near the top of the cooler, the duct including a pipe section extending downwardly from the top of the last-named leg of the trap, and a pipe extending downwardly from the bottom of the cooler and communicating with the last-named pipe section below the cooler, whereby condensed refrigerant passing through the trap may move upwardly through the top of the last-named leg of the trap downwardly through the pipe section and upwardly through the last-named pipe thus returning to the cooler.

21. Refrigerating apparatus of the class described comprising a refrigerant circuit including a cooler, a condenser and means to pump refrigerant about said circuit, said circuit also including a return duct extending from the condenser to the cooler, said duct having a trap therein arranged to provide one leg containing a column of liquid refrigerant and an opposite leg to contain a column of pressurizing liquid so that the refrigerant may pile up in the first-named leg to overbalance said column sufficiently to permit refrigerant to pass through the trap and to the top of said column, the upper part of the last-named leg of the trap extending upwardly substantially to a level with the upper part of the cooler, a drain pipe extending downwardly from the bottom of the cooler, and a pipe section connecting the upper part of the last-named leg of the trap with said drain at a point spaced below the cooler whereby condensed refrigerant passing through the trap may rise upwardly substantially to the level of the top of the cooler and may then pass downwardly through said connection and through the upper part of said drain to the cooler.

LYMAN F. WHITNEY.
